UNITED STATES PATENT OFFICE.

CARLOS DULCHÉ, OF LOS ANGELES, CALIFORNIA, ASSIGNOR OF THIRTY-THREE PER CENT TO JORGE VERA-ESTANOL, SIXTEEN AND ONE-HALF PER CENT TO JUAN B. CASTELAZO, JR., AND SIXTEEN AND ONE-HALF PER CENT TO FRANCISCO CASTELAZO, ALL OF LOS ANGELES, CALIFORNIA.

BOTTLE-CASE-LOADING MACHINE.

Application filed August 24, 1925. Serial No. 52,125.

My invention is a bottle case loading machine particularly adapted to load milk or other types of bottles into a case for delivery or shipping.

My invention comprises a comprehensive machine for feeding bottles over a case, retaining the bottles elevated at a high level until a sufficient number are grouped together in a basket type holder to fill the case and then automatically dropping the bottles into the case. The bottles are retarded in their drop so that they may not be broken, cracked or injure the case. The cases are automatically fed to the machine directly below the bottle holding basket and after being filled are automatically discharged from the machine.

Described and outlined more fully the machine has a bottle feeding belt or apron with a series of distributing passages with mechanism to distribute the bottles sidewise to a plurality of passages from a substantially single entrance. The bottle holding basket has a series of segmental hinged tracks to support the bottles so that they may be passed beyond the apron to a position above the case, the bottles being pressed along by succeeding bottles shoving them into position. The bottles cannot drop into the case until the bottle holding basket is completely filled when an electric circuit is established releasing a trigger which allows the tracks to swing downwardly and drop the bottles through a contracted resilient chute.

The empty cases are fed intermittently to the machine by a high cross conveyor on to a balanced table. This table becomes depressed when the bottles are loaded therein and is immediately carried out of the machine on an endless belt type of conveyor. I show an electric drive for the intermittent cross conveyor having an electric motor therefor with a circuit breaker so arranged to break the circuit when a case is in position to be loaded and thus stop the movement of the conveyor and the circuit is not made until the case has been lowered after being filled, discharged from the table and the table raised to the high position.

The objects of my invention may therefore be stated as providing a machine for feeding and distributing bottles to a bottle

holding basket having spaces for a plurality of bottles in accordance with the size of the case and the number of bottles to be placed therein in accordance with the particular trade, retaining the bottles in the basket until it is completely filled and then automatically dropping the bottles through restricted chutes into the bottle cases. The objects also include restraining the bottles from being fed into the basket until the bottles are released from the basket to drop into the bottle cases and the tracks are again in the original position. A further object is in the automatic feeding of cases to and away from the machine.

My invention will be more readily understood from the following description considered in connection with the drawings, in which:

Figure 1 is a plan view of the entire machine in the direction of the arrow 1 of Fig. 2, showing the feeding apron with the distributor for passing the bottles into different passages, the dumping bottle basket and the in and out conveyors.

Fig. 2 is a side elevation of Fig. 1 in the direction of the arrow 2 of Fig. 1, showing the feeding-in conveyor in section.

Fig. 3 is an end elevation showing the discharge end of the machine taken in the direction of the arrow 3 of Fig. 1.

Fig. 4 is a vertical longitudinal section taken on the line 4—4 of Fig. 1 in the direction of the arrows 4, showing especially the bottle holding basket, the restricted chutes for the bottles, the balanced table for the cases and the feeding-out conveyor.

Fig. 5 is a horizontal section on the line 5—5 of Fig. 2, showing in particular the table for receiving the cases at the high level, holding them in position and the endless belt type conveyor for carrying the loaded cases out of the machine.

Fig. 6 is a vertical longitudinal section in part side elevation, similar to Fig. 4, showing a filled case being discharged by the feeding-out conveyor.

Fig. 7 is an end elevation partially in section similar to Fig. 3, showing the mechanism operated by the dumping basket tracks on release of the holding latch by the electrically controlled electro-magnet operated

by the bottles, dropping the bottles into a case. This figure is on an enlarged scale from Fig. 3.

Fig. 8 is an enlarged cross section in a vertical plane on the line 8—8 of Fig. 1 in the direction of the arrows, showing the bottle basket with the bottle supporting tracks in their bottle carrying position, with the bottle restrainers in their retracted position allowing feeding of the bottles and also showing the resilient chutes for dropping the bottles.

Fig. 9 is a vertical cross section similar to Fig. 8 showing the bottle basket at the moment of dropping the bottles and with the bottle restrainer set to block the feeding of bottles.

Fig. 10 is a diagrammatic view illustrating the electric circuit established by the filling of the bottle basket with the bottles and indicating an electro-magnet controlling the track controlling latch in its locked position.

Fig. 11 is a detail of the circuit breaker controlling the electric motor for operating the feeding-in conveyor, showing the automatic setting of the switch but not the making of the circuit, that is with the circuit open on the lowering of the case table.

Fig. 12 is a detail similar to Fig. 11, showing the making of the circuit by the rise of the balanced case table.

Referring particularly to Figs. 1, 2 and 3, the machine is housed in a frame 1, having base longitudinal bars 2, intermediate bars 3, top rails 4, front posts 5, intermediate posts 6, rear posts 7, back leg 8 and cross grid 9 and front bar 10. These are preferably formed into either a cast, side frames suitably connected and braced together or by structural bars secured together to form a solid machine frame.

The bottle feeding and distributing mechanism is constructed substantially as follows, having reference particularly to Figs. 1, 2, 4. An endless conveying belt or apron 11 is mounted on the driving roller 12, and idler roller 13, positioned crosswise in the frame so that the upper surface of the belt passes above a belt supporting web 14 built into the frame transversely of the belt or apron. The belt travels in the direction of the arrow indicated adjacent thereto in Fig. 4 and is driven by the belt 15 operating over a pulley 16 on the shaft 17 of the driving roller 12, the said belt being operated by a drive pulley 18 mounted on a transverse shaft 19 as will be hereafter set forth.

A series of guide rails 20 are positioned longitudinally of the machine, being attached to the front bar 10 and the stop bar 21 at the back of the machine above the top of the frame so that the rails extend forwardly over the belt as indicated in Fig. 4. The outer rails are drawn inward in a

plurality of curves 22, forming the straight guide rails 23 at their forward end, thereby making a feeding-in throat 24 at the forward end of the machine over the belt. The machine is constructed with four passages 70 25 between the guide rails 20 so that four rows of bottles will be fed over the cases and the central rail has a diverting nose 26 formed by spreading the guide rail located in the central position of the machine. This 75 nose has a pivoted deflecting finger 27 having a spreading base 28 and secured to the nose by the pivot pin 29. The ends of the intermediate guide rails 30 have similar deflecting fingers on their forward ends to 80 shift the bottles on each side of the said rails between the outer rails 20 and the mid position rail 31.

The manner of operation of the feeding apron and distributing passages is substantially as follows:—The bottles may be fed by any type of mechanism into the machine to enter the throat 24. If the deflecting finger 27 is in the position shown in Fig. 1, the bottles will be fed to the opposite passage and engage in the spreading base 28 swinging the finger in the opposite direction. The bottles will then be engaged by the deflecting fingers on the ends of the intermediate guide rails 30 and deflected either to the left 90 or to the right according to the position of the finger to locate the bottles in the several passages between the guide rails. It will thus be seen that the bottles entering through the throat are alternately deflected 95 left and right and that these bottles are likewise again deflected, each bottle in an alternate direction so that the bottle basket will be uniformly filled.

The bottle holding and dumping basket is 105 constructed substantially as follows, having reference particularly to Figs. 1, 4, 7, 8 and 9. As above described, the longitudinal guide rails 20, 30 and 31 are extended to the stop bar 21, forming a bottle holding basket 110 designated generally by the numeral 32. The outside rails 20 are provided with recesses 33 formed in sections with lugs 34, therebetween, said lugs having bushings 35 through which may be inserted lengthwise 115 the rock shafts 36. The intermediate guide rails 30 have depending lugs with bushings 35 therethrough in which are located similar rock shafts 36. These rock shafts have a series of tracks 38 formed of angular plates 120 with a wearing strip 39 extending upwardly. These tracks are shown secured to the rock shafts 36 by pins 40.

A series of bridging plates 41 are secured to the upper edge of the front bar 10 and 125 extend close to the belt 11 as it passes over the driving roller 12. These plates carry the bottles from the belt to the tracks 38. Narrow cross bars 42 are secured across the frame of the machine and carry rings 43 130

having spring wires 44 attached thereto forming a resilient contracted chute 45 below each bottle positioned, below each section of track 38. At the feeding-in 5 end of the machine adjacent the bridging plates 41, a series of stopping fingers 46 are secured to the rock shaft substantially at right angles to the tracks 38 and engage stop springs 47 which are constructed of a resilient strip of metal secured to the top of the outside guide rails 20 and intermediate guide rails 30. These stop springs normally 10 occupy the position shown in Fig. 8 being tensioned to retract to such position. De- 15 pressions 48 are formed in these rails so that the fingers 46 may swing therein when the tracks are in their upper or carrying position shown in Fig. 8.

The rock shafts and hence the dumping 20 tracks are controlled substantially as follows:

Having reference particularly to Figs. 1, 3, 4, 7 and 10, a cam 49 is secured to the end of each rock shaft, preferably in an adjustable manner, being held in position by a set screw 50 and as the tracks are illustrated as dropping in different directions of movement, the cams face in opposite directions. A latch bar 51 is supported from standards 52 secured to the cross grid 9 by means of adjustable links 53 pivoted at 54 to the tops of the standards and swivelly connected at their lower ends 55 to the latch bar. The pivot pins are preferably readily removable 25 so that the links may be accurately adjusted in length by threading one into or out of the other in the manner of turnbuckles. Tension springs 56 are positioned between the pin 55 and the cross grid 9 normally 30 drawing downwardly on the latch bar and thereby pressing the cams 49 into the position shown in Figs. 1 and 3, thereby holding the tracks 38 in their horizontal position as shown in Figs. 1 and 8, so that the bottles 35 may be fed into the basket through the medium of the apron 11 causing the following bottles to press the leading bottles forward.

The electric trip mechanism to dump the bottles is constructed substantially as follows, having reference particularly to Figs. 1, 4 and 10:—A latch hook 57 is secured to the back face of the latch bar 51 and is engaged by a hooked head 58 mounted on the armature 59, of an electro-magnet 60, which latter is supported in a housing 61 mounted on the cross grid 9. A series of push button switches 62 are mounted on the front face of the stop bar 21 in position to be engaged by the bottles as they are pressed into the machine.

The electric circuit is shown particularly in Fig. 10 and is constructed as follows:—Electric leads 63 form a circuit from the source of power 64 through the electro-magnet 60 and through each of the switches of

the push button type 62. These switches are all in series so that it is necessary for them all to be closed before the circuit is established. Therefore the bottles must be pressed completely and tightly into the bottle holding basket 32 so that there will be as many bottles as there are chutes 45 and as are required to fill the case, and moreover, the bottles will be properly centered. When the bottles in the different passages 25 press 70 their individual push button to establish the circuit, the electro-magnet is energized withdrawing the armature and hook 58, thereby releasing the latch hook 57 and allowing the bottles to drop, moving the tracks from the 75 position shown in Fig. 8 to that shown in Fig. 9 and shifting the cams 49 from the position shown in Fig. 3 to that of Fig. 7. The bottles are thus dumped into a case and in the rocking movement of the rock bars 80 the stopping fingers 46 are moved from the position shown in Fig. 8 to that shown in Fig. 9, thus thrusting the stop springs 47 across the bridging plates 41 and thus preventing the bottles being filled into the bottle 85 holding basket.

When the bottles have been dropped into the case the springs 56 draw the latch bar 51 downwardly and rock the cams 49 from the position shown in Fig. 7 to that shown 90 in Fig. 3, in which operation the latch hook 57 and the hooked head 58 become engaged due to a compression spring 65 pressing the armature of the electro-magnet forwardly. Thus the tracks are locked to permit feeding 95 of the bottles and there is no barrier in their way.

The mechanism for feeding the cases into the machine is constructed substantially as follows, having reference particularly to Figs. 1, 2, 3, 5 and 7:—A conveyor frame 66 has an outside pair of legs 67 secured to the floor of the building and a bracket 68 secured to the side of the main machine frame preferably to the posts 6 and 7. A series of rollers 69 are mounted in the frame 66 on each side thereof and are freely rotatable and conveniently placed whereby an attendant may place empty cases thereon. Sprocket gear wheels 70 are journaled preferably by having shafts 71 and 72 journaled respectively to the legs 67 and the bracket 68. A sprocket chain 73 having feeding pins 74 are operated by the sprocket wheels to feed the empty cases into the machine as indicated by the arrow in Fig. 3. The driving mechanism is hereafter described in detail.

The balanced table for supporting the empty case and in lowering it to the feeding-out conveyor is constructed substantially as follows, having reference particularly to Figs. 2, 3, 4, 5, 6 and 7:—A table 75 is constructed with side rails 76 slidable on rods 77 as shown in Figs. 3, 4 and 5. The side 125

rails are connected by a drop brace 78 connected from one side to the other in order to hold the side panels rigid, one in regard to the other causing uniform motion thereof. Inwardly extending arms 79 and 80 are attached to the side rails and extend close to the centrally positioned out-feeding conveyor hereafter described. Guide plates 81 are pivotally connected to the arms 79 as indicated at 82 and have rearwardly projecting shanks 83.

A pair of lever arms 84 and 85 are pivoted by means of pivot pins 86 on brackets 87 secured to the intermediate bars 3 of the main frame of the machine. The lever arms 84 have counter-weight arms 88 connected therewith with counter-weights 89 adjustably mounted thereon by means of set screws or similar devices. A link 90 connects the two lever arms 84 and 85 and on the pintles 91 carries rollers 92 which bear on the under-surface of the side rails 76 of the table 75, thereby always tending to elevate the table.

The out-feeding conveyor is constructed substantially as follows, having reference particularly to Figs. 1, 2, 3, 4, 5 and 6:—A main shaft 93 is mounted in the frame and is shown journaled at the top of the back leg 8 where it joins the intermediate bars 3. This shaft carries the main pulley 94 through which a drive is carried to the machine operating the sprocket gear wheel 95, and by means of the sprocket chain 96 the driven sprocket gear 97 fixed on the transverse shaft 19. As formerly mentioned the drive is continued by the belt 15 operating the pulley 16 which in its turn transmits motion to the apron 11.

The sprocket chain 96 carries a series of projections 98 which project upwardly through a slot 99 in a plate 100, which plate is supported by a pair of brackets 101 on the fixed rod 102 extending transversely across the frame. The plate 100 thereby serves as a support for the boxes of filled bottles after the table 75 has been depressed by the weight of the filled bottles. The shanks 83 of the guide plates 81 contact with the rod 102 and thereby release the guide plates from the edge of the box or case as shown in Fig. 6 so that the movement of the sprocket chain 96 in the direction of the arrow moves the filled case out of the machine.

The electrical control and motor drive for the feeding-in mechanism is constructed substantially as follows, having reference particularly to Figs. 2, 3, 5, 11 and 12:—An electric circuit breaker designated generally by the numeral 103 shown particularly in Figs. 3, 11 and 12 has a fixed insulating plate 104 secured to a bracket 105 which is carried by a longitudinal brace 106 secured between the intermediate posts 6 and the

rear post 7 on the opposite side of the machine from the feeding-in conveyor. The bracket 105 carries a pair of lugs 107 to which is pivoted a switch lever 108 having an outstanding projection 109 on one side of the pivotal point and a plug contact 110 mounted on the other end on an insulating plate 111. A spring 112 is tensioned to normally establish an electric circuit between the socket members 113 and 114, the member 113 having a binding post 115 connected to a lead wire 116. The other lead wire of the circuit 117 is connected to a binding post 118 having a cap 119 on the same side of the insulating plate 104. A strut 120 is secured to the balanced table 75, being attached to the side panels 76 on the opposite side from the feeding-in conveyor and carries an insulating strip 121 at its upper end with a conducting bridging bar 122 which is adapted when in its uppermost position as shown in Fig. 12 to bridge the space between the socket member 114 and the cap 119 and in such position establish an electric current which will operate the electric motor.

The motor is designated generally by the numeral 123 and by means of the pinion 124 drives a gear 125 on the countershaft 126, which latter has a gear 127 meshing with the gear 128 on the shaft 72 which drives the sprocket wheels 70 of the feeding-in conveyor sprocket chain 73. The action of the circuit breaking mechanism above described is substantially as follows:—If the table 75 is in its uppermost position and no box is positioned thereon, the circuit will be established through the leads 116, post 115, socket member 113, plug 110 socket member 114, bridging plate 122, cap 119, post 118 and electric lead 117 to the electric motor, which will operate to move the feeding-in conveyor and when a case contacts with the projection 109 of the switch lever 108, the circuit will be broken as shown in Fig. 3 by the withdrawal of the plug 110 from the socket members 113 and 114. Thus the feeding conveyor will be brought to rest. A coil spring transmission 129 is used to transmit motion from the motor to the pinion 124 so that the abrupt stopping and starting of the motor will not cause any damage. As shown in Fig. 3, the box on the table 75 has been completely shoved over by contacting with the case on the feeding-in conveyor mechanism. Hence after a case has been filled and lowered on to the feeding-out conveyor and the table has been elevated to its uppermost position, an empty case is in position to be immediately fed forward thereon.

It will thus be seen that I have provided a machine for loading bottles into a case which is automatic in that the bottles are fed into the bottle holding basket, retained therein until all the rows are completely

full when the bottles at the end of each row press against the electric switches making a series circuit which actuate the electric trip mechanism allowing the bottles to drop 5 into an empty case. The weight of the loaded case causes the supporting table to move downwardly and the case to be removed by the out-feeding conveyor. Also on the upward movement of the table an empty 10 case is fed into the machine by starting the electric motor is stopped stopping such conveyor and when the case is in position the electric motor is stopped stopping such conveyor. 15 My invention may be considerably changed in general construction and in specific functions to suit loading of different types of cases or bottles and for other purposes, without departing from the spirit of my invention as set forth in the specification and defined in the claims. 20 Having described my invention, what I claim is:

1. A bottle case loading machine comprising in combination a machine framework, a conveyor for feeding bottles, a bottle holding basket, means to retain bottles therein and means actuated by the bottles after the basket is filled to drop the bottles through 30 the bottom of the basket into a case.

2. A bottle case loading machine comprising in combination a machine framing, a bottle holding basket having means for holding a plurality of rows of bottles therein, 35 means for feeding bottles to the basket, a table positioned below the basket to hold a case and means operated by the bottles when the basket is filled to actuate a dumping mechanism to drop the bottles into the case.

40 3. A bottle case loading machine as claimed in claim 2, having in addition means to feed the bottles to the different rows, said feeding means exerting a pressure on the bottles in the basket to operate the means actuating the dropping mechanism.

45 4. A bottle case loading machine comprising in combination a machine framework, a bottle holding basket having a plurality of dumping tracks, a conveyor apron to feed the bottles to the bottle holding basket on the said tracks, means to distribute the bottles on to the different tracks, a series of electric switches operated by the bottles to form a circuit in series when all the switches 50 are closed, and establish an electric circuit, said circuit having an electric device therein and means to trip the track and allow dropping of the bottles through the closing of the said switches.

50 5. A bottle case loading machine comprising in combination a machine framework, a plurality of guide rails extending longitudinally of the framework forming a series 55 of passages therebetween, a conveyor apron operating under the forward end of the

guide rails, means associated with the guide rails to distribute bottles laterally to the different passages, a table adapted to hold an empty case, dumping tracks in the passages above the table, a stop bar at the end of the 70 passages, electric switches at the end of each passageway mounted on the stop bar, said switches being connected in series, an electrically operated trip mechanism to operate the dumping tracks, the said apron and dumping 75 tracks permitting bottles to be fed into the machine to cause the bottles on the dumping tracks to operate the electric switches to thereby drop the bottles into the case. 80

6. A bottle case loading machine as claimed in claim 5, in which the dumping tracks comprise longitudinally extending shafts, track elements mounted thereon, cams on the ends of the shafts, a latch bar movably mounted and engaging the cams and an electro-magnetic device engaging the latch bar. 85

7. A bottle case loading machine as claimed in claim 5, in which the table is 90 supported on counter-balanced movable supporting elements adapted to lower the table when the case is filled with bottles and to elevate the table when the case is removed.

8. A bottle case loading machine as 95 claimed in claim 5, in which the table is mounted on counter-balanced lever arms adapted to permit the lowering of a case when filled with bottles, a feeding-out conveyor operable underneath the table, having means to engage a case when the table is lowered and feed it out of the machine, said counter-weight elevating the table when the case is removed. 100

9. A bottle case loading machine comprising in combination a machine framing, a passageway extending longitudinally of the machine, a table, adapted to hold an empty case, a series of bottle retaining devices in the said passageway over the table, an electric switch at the end of the passageway, means to press a row of bottles in the passageway against the electric switch and an electrically operated trip device to drop the bottles into a case on the table when the said passageway is filled with bottles over 105 the bottle retaining means. 110

10. A bottle case loading machine comprising in combination a machine framing, a bottle holding basket having a plurality of longitudinal passageways, a series of connected dumping tracks in each passageway, each section of track adapted to hold a bottle, an electric switch at the end of each passageway, said switches being connected in series, means to press the bottles longitudinally of the passageways against the switches and electrically operated means to actuate the dumping tracks to drop the bottles through the bottle holding basket. 120 125 130

11. A bottle case loading machine as claimed in claim 10, in which the tracks comprise a plurality of shafts, track elements secured thereon, a latch bar operatively connected to the shafts and an electro-magnetic device to operate the latch bar when all the switches are closed to allow the dropping of the bottles through the basket.
12. A bottle case loading machine as claimed in claim 10, in which the tracks comprise a plurality of longitudinally extending oscillatable shafts, track elements secured thereto, cams on the ends of the shafts, a latch bar movably mounted and engaging the cams, an electro-magnetic trip device to release the trip bar when all the switches are closed and means to move the trip bar to its normal position and thereby oscillate the track elements to their normal position after dropping bottles.
13. A bottle case loading machine comprising in combination a machine framework, a plurality of guide rails extending lengthwise of the framing and forming a plurality of parallel passageways, oscillatable shafts positioned below said guide rails, a series of plates attached to each shaft forming tracks adapted to allow travel of bottles resting with their base on the said plates, a series of cams on the ends of the said shafts, a latch bar operatively mounted on standards secured to the framework, said latch bar bearing against the cams, a latch hook device operatively connected with the latch bar, an electro-magnetic device to operate the said latch hook device and a series of electric switches forming an electric circuit with the electro-magnetic device only when all the passageways are filled with bottles and the bottles are pressed lengthwise of said passageways.
14. A bottle case loading machine as claimed in claim 13, having in addition a continuously moving apron adapted to convey bottles to said passageways, means to distribute bottles laterally to the passageways and press the bottles against the switches and means operated by the movement of the tracks in dumping to restrain the bottles to stop the movement of the bottles off the apron.
15. A bottle case loading machine comprising in combination a machine framing, means to feed empty cases into the framing, a bottle holding basket positioned above a case when located in the framing, means to load bottles into the said basket, means operated by the bottles when the basket is filled to cause the dropping of the bottles through the basket into a case and means to convey a filled case out of the machine framing.
16. A bottle case loading machine comprising in combination a machine framing, a feeding-in conveyor for empty cases, an electric motor to operate said conveyor, a movable table at the end of the conveyor in the framing, a bottle holding basket having a plurality of passageways positioned above the table, dumping means to retain bottles in the basket, a movable apron for feeding bottles into the basket, an electro-magnetic means operated by the bottles when all the passageways are filled, to allow dumping of the bottles into a case on the said table, said table being depressed by the weight of the filled case, and a continuously operating feeding-out conveyor to engage the filled case and remove it from the machine framing.
17. A bottle case loading machine as claimed in claim 16, having in addition a circuit breaker positioned to engage a case when fed on to the table and stop the electric motor, and means connected to the table to make an electric circuit through the circuit breaker on the upward movement of the table after discharging the filled case.
18. In a bottle case loading machine, a table adapted to support an empty case, counter-balancing means to retain the table normally in elevated position, a feeding-in conveyor having an electric motor to operate same, an electric circuit breaker positioned to be engaged by an empty case when fed on the elevated table to break the circuit and stop the motor and a bridging plate operatively connected to the table adapted to establish an electric circuit when the empty table is in its uppermost position and thereby start the motor to feed an empty case on the table.
19. In a bottle case loading machine as claimed in claim 18, having in addition a continuously operating feeding-out conveyor located below the table, adapted to engage a filled case on the depression of the table and remove it off the table and out of the machine.
20. In a bottle case loading machine, a machine framing, a table having a pair of spaced panels at opposite sides of the framing, a pair of counter-balancing lever arms pivotally mounted in the frame and engaging the said panels adapted to normally hold the table in elevated position, guide rods to guide the table in its upward or downward movement, a feeding-out conveyor positioned in the framing below the table, guide plates pivotally connected to the table adapted to position an empty case thereon and means actuated by the lowering of the table through the weight of a filled case to actuate the guide plates to release the case and means on the feeding-out conveyor to engage a case and move it out of the machine framing.
21. In a bottle case loading machine as claimed in claim 20, having in addition a plate having a slot therethrough in which the feeding-out conveyor operates, said plate being positioned between the panels of the

- table and adapted to receive a filled case on the depression of the table and permit engaging of said case by the said feeding-out conveyor.
22. A bottle case loading machine comprising in combination a machine framework, a bottle holding basket having a plurality of passages and a series of dumping bottoms in each passageway, a counter-balanced movable table to support an empty case, a conveyor to feed an empty case on the table, a feeding-out conveyor positioned below the table, electric switches at the end of each passageway and means to press the bottles against the electric switch connected in series, to establish an electric circuit to actuate the dumping bottom of the basket and discharge the bottles into the case, the filled case causing the lowering of the table to engage the case with the feeding-out conveyor.
23. A bottle case loading machine comprising in combination a bottle holding basket having dumping tracks adapted to drop bottles therethrough, a series of guide rails dividing the basket into a plurality of passages, the guide rails being contracted towards each other forming a narrow entrance throat, a continuously moving apron conveyor positioned below the guide rails and pivotally mounted deflecting fingers on the ends of the guide rails adapted to shift bottles into adjacent passages by the movement of the apron.
24. A bottle case loading machine as claimed in claim 4, having a latch bar, cams connected to the track operatively engaging the latch bar, said latch bar being released by the electrical device and a series of springs to return the latch bar and the cams and tracks to their normal position.
25. In a bottle case loading machine as claimed in claim 18, in which the counter-balancing means comprises a system of levers with a counter-weight thereon, operatively connected to the table, said system of levers permitting the table to swing downwardly when a case is filled and to swing upwardly when the case is removed from the table.
26. In a bottle case loading machine, a bottle holding basket, a series of rings in the basket, spring wires depending from the said rings, tracks supporting a bottle above each ring and means to trip the tracks to allow dropping of the bottle through the rings, said bottle being retarded by the said springs.
27. A case loading machine comprising in combination a machine framework and a holding basket, means to retain the containers therein until said holding basket is filled with the number of containers desired and means to permit dropping of the bottles through the bottom of the basket into a case.
28. A case loading machine comprising in combination a machine framework and a holding basket, means actuated by the containers after said holding basket is filled with the number of containers desired, to let drop said containers through the bottom of the holding basket into a case.
29. A case loading machine comprising in combination a machine framework, a conveyor and a holding basket, means actuated by the containers to distribute automatically said containers in two or more rows as it may be desired, means to retain the containers in the holding basket until said holding basket is filled with the number of containers desired.
30. A case loading machine comprising in combination a machine framework, and a holding basket, means to retain the containers therein until the holding basket is filled with the number of containers desired, means actuated by the containers after the holding basket is filled with the number of containers desired, to let drop said containers through the bottom of the holding basket into a case.
31. A case loading machine comprising in combination a machine framework, a conveyor and a holding basket, means actuated by the containers to distribute automatically said containers in two or more rows as it may be desired, means to retain the containers in the holding basket until said holding basket is filled with the number of containers desired, means actuated by the containers after said holding basket is filled with the number of containers desired, to let drop said containers through the bottom of the holding basket into a case.

In testimony whereof I have signed my name to this specification.

CARLOS DULCHÉ.
